Matthew W. Mitchell(57) **CLAIM**

The ornamental design for a landscape edging, as shown and described.

DESCRIPTION

FIG. 1 is a front isometric view of the landscape edging of the present invention;

FIG. 2 is rear isometric view thereof;

FIG. 3 is a front view thereof;

FIG. 4 is a rear view thereof;

FIG. 5 is a top plan view thereof; and

FIG. 6 is a bottom plan view thereof.

FIG. 7 is an enlarged right-side view thereof; and,

FIG. 8 is an enlarged left-side view thereof.

The broken lines in the drawings represent portions of the landscape edging that form no part of the claimed design.
